(57) **CLAIM**

The ornamental design for a transportation and storage container, as shown and described.

DESCRIPTION

FIG. 1 is a front, right perspective view of a transportation and storage container according to the design, the front, left perspective view being mirror symmetrical;

FIG. 2 is a front view thereof, the rear view being identical;
FIG. 3 is a side view thereof, the opposite side view being identical;

FIG. 4 is a top view thereof;

FIG. 5 is a bottom view thereof.

FIG. 6 is a bottom perspective view thereof, with the top portion removed for convenience of illustration; and,

FIG. 7 is an enlarged view of an exploded corner portion of the transportation and storage container.

The broken lines around the perimeter of FIG. 7 illustrates the bounds of the enlarged view. The remaining broken lines illustrate portions of the transportation and storage container. None of the broken lines form part of the claimed design.
